UNITED STATES PATENT OFFICE.

EMIL STAHELIN, OF CHICAGO, ILLINOIS, ASSIGNOR TO WALGER AWNING COMPANY,
OF CHICAGO, ILLINOIS, A CORPORATION OF ILLINOIS.

AWNIN.

1,250,239.

Specification of Letters Patent. Patented Dec. 18, 1917.

Application filed August 3, 1916. Serial No. 112,956.

To all whom it may concern:

Be it known that I, EMIL STAHELIN, a citizen of the United States of America, residing at 215 E. 56th St., Chicago, county of 5 Cook, and State of Illinois, have invented new and useful Improvements in Awnings, of which the following is a specification.

My invention relates to improvements in 10 awnings and particularly to those in which a portion of the fabric is parallel to the window and a portion is held at an angle thereto when in use. An awning of this 15 type is shown in U. S. Patent 801421—Walger *et al.*

In my improved awning, I provide means for operating the device from inside a screen or even inside a window without opening either as all parts are self alining at all 20 times. I obviate the use of all springs and provide apparatus in which no pockets are formed in which dust and dirt might accumulate to interfere with its proper operation. In my device all braces and arms 25 are suspended from above and therefore cannot project to interfere with anyone passing under the awnings. Furthermore, in supplying a device in which all parts are movably guided, I obviate the danger of any 30 parts leaving their proper alinement during manipulation in case there is any appreciable wind at such time. I provide an awning which can be adjusted to numerous positions when in use by a very simple manipulation. In fact, but two operations are necessary to lower it into position and retain it 35 there.

In the accompanying drawings which form part of this specification, Figure 1 represents the complete awning in place rolled up; Fig. 2 is a side elevation of certain parts on an enlarged scale at a certain stage in lowering of the awning; Fig. 3 shows the complete awning fully distended and dotted lines illustrate the releasing action; Fig. 4 is a top plan view of the fixtures at one side under the same conditions illustrated in Fig. 3; Fig. 5 is a front elevation on an enlarged scale of the same parts shown in Fig. 50 2 but adjusted about as they appear in Fig. 3; Fig. 6 is a side elevation similar to Fig. 2 but illustrating the completion of the release action; Fig. 7 is a side elevation illus-

trating certain of the parts as they would appear in the course of the rolling up of the 55 awning.

Referring to the drawings in which like parts are designated by the same numerals 1 shows a window frame having attached thereto by suitable roller brackets a roller 2 on which the awning fabric 3 is rolled, this roller being under the control of a tension member 4 which may be a rope or cord. A hook 5 of any suitable shape is provided to fasten the rope when the device is in use. 65 This hook may be replaced by a locking pulley. The cross-rod 7 which is attached to the window frame acts as a guide and support for the awning fabric. The fabric 3 is attached to a rod 8 which is supported by arms 70 9 pivotally mounted on trunnions 10 which slide on the guide rods 6. These rods are attached to the window frame 1 in any suitable manner. The two sides of the awning support frame, and retaining mechanism are similar. 75 Each side has a brace 11 pivotally mounted on the arm 9 and is caused to follow the guide rod 6 by means of the stirrup 12. One end 17 of the stirrup 12 projects through the brace 11 to act as a stop for the arm 9 at certain 80 times. A ratchet rack 15 is pivotally attached to the bracket frame 13 which is attached to the window frame in any suitable manner. The bracket frame 13, guard 16 and ratchet 15 are of such relative proportions that the pin 14 attached to brace 11 will enter from above between the guard 16 and the ratchet 15 when the awning is being lowered into its open position, (Fig. 2) and will slip out between them at the bottom 90 when the awning is being closed (see dotted lines, Fig. 3). To accomplish the latter, the guard 16 and the ratchet 15 are pivotally attached to the bracket 13 by the pin 18 and the bracket 13 is formed with a beveled edge 95 19 which guides the pin 14 out to become free of the ratchet. The ratchet 15 may be a part of the frame 13. Then the guard 16 only is pivoted.

The cord 4 may be attached either on the 100 inside of the window frame or outside.

When not in use the arm 9 and brace 11 are folded upward and are raised out of the way when the fabric is rolled on roller 2 (Fig. 1) by manipulating cord 4. In order 105 to open my improved awning the cord 4 is

released from the hook 5 and the fabric is unrolled from the roller by the weight of the braces and arms, until the trunnions 10 have slid to the bottom of the guide rods 6. 5 The arms 9 then swing out and downward and the pin 14 of the stirrup 12 falls between the guard 16 and the ratchet 15 (Fig. 2). When the awning has reached the position desired the cord 4 is wound around the hook 5 thus holding the pin 14 in one of the teeth of the ratchet by placing a tension on the fabric. Since the brace 11 is guided by means of the rods 6 and stirrups 12, the pin 14 must enter between the guide and ratchet although a wind may blow under the fabric tending to throw it out of alignment. To fold the awning tension on the rope 4 is relieved permitting the arm 9 to fall below 90°. This draws the brace down 10 along the ratchet until the pin 14 strikes the bevel portion 19 of the bracket 13. The pin 14 in traveling along the bevel portion causes the ratchet and guard to swing outwardly on the pin 18 so that the pin 14 15 may pass out at the bottom from between the guard and ratchet which then fall back into place (dotted lines, Fig. 3), the pin 14 dropping down upon a shoulder or ledge of the bracket 13 (Fig. 6). The outward swing of the ratchet and guard is limited by 20 abutment of the lower end of the ratchet bar against a shoulder formed by a laterally turned lower portion of the bracket 13, said laterally turned portion 20 extending in 25 ward from said shoulder so as to constitute together with the overhanging portion of the bracket a guide or keeper for the ratchet bar. By pulling on rope 4, the arm 9 is caused to swing upward as the fabric is 30 rolled on the roller 2 and the brace 11 is caused to slide upward on the guides 6. The pin 14 now passes along the outside of the guard 16 (Fig. 7) because there is sufficient play in the stirrup to permit it. The arms 9 35 are raised until they strike the projecting pins 17 supplied by the stirrup ends (Fig. 1) whose purpose is to prevent the arms becoming entirely perpendicular as such position might be a dead center and prevent the free 40 falling of the awning. After the arms 9 have encountered the pins 17, the entire awning is raised out of the way, the trunnions with the arms 9 and braces 11 being 45 slid along the guide rods 6 until the entire awning has been rolled up.

I claim as new and desire to protect by Letters Patent:

1. The combination with the awning fabric and its supports including a guide and 50 an outward swinging arm; of a brace pivoted to said arm and extending on the upper side thereof and inwardly; and holding means located at an elevated point and with which the inner end of said brace is adjust- 55 ably engageable, and from which it is dis-

engageable by the lowering of the arm, said inner end of the brace adapted to be carried upwardly beyond said holding means by the raising of said arm.

2. The combination with the awning fabric and its supports including a guide and an outwardly swinging arm; of a brace pivoted to said arm and extending on the upper side thereof and inwardly, a ratchet with which said brace engages in the lowering of the awning, and a movable guard adjacent the ratchet and adapted to be displaced by the brace upon abnormal lowering of the awning, said brace escaping from the guard and adapted to travel upwardly along the outer side thereof in the raising of the awning from its abnormal lowered position. 70

3. The combination with the awning fabric and its supports including a guide and an outwardly swinging arm; of a brace pivoted to said arm and extending on the upper side thereof and inwardly, a ratchet with which said brace engages in the lowering of the awning, a movable guard adjacent the ratchet and behind which the brace engages, and means associated with the ratchet and guard for disengaging the brace from the ratchet and thereby displacing the guard, said brace escaping from the guard and adapted to travel upwardly along the outer side thereof in the raising of the awning from its abnormal lowered position. 85

4. The combination with the awning fabric and its supports including a guide and an outwardly swinging arm; of a brace pivoted to said arm and extending on the upper side thereof and inwardly, a ratchet with which said brace engages in the lowering of the awning, a movable guard adjacent the ratchet and behind which the brace engages, and a cam associated with the ratchet and guard for disengaging the brace from the ratchet and thereby displacing the guard, said brace escaping from the guard and adapted to travel upwardly along the outer side thereof in the raising of the awning from its abnormal lowered position. 100

5. The combination with the awning fabric and its supports including a guide and an outwardly swinging arm; of a brace pivoted to said arm and extending on the upper side thereof and inwardly, a ratchet with which said brace engages in the lowering of the awning, and a pivoted depending guard adjacent the ratchet and adapted to be displaced by the brace upon abnormal lowering of the awning, said brace escaping from the guard and adapted to travel upwardly along the outer side thereof in the raising of the awning from its abnormal lowered position. 105

6. The combination with the awning fab- 110

- ric and its supports including a guide and an outwardly swinging arm; of a brace pivoted to said arm and extending on the upper side thereof and inwardly, a ratchet 5 with which said brace engages in the lowering of the awning, a movable guard adjacent the ratchet and behind which the brace engages, and means associated with the ratchet and guard for disengaging the brace from 10 the ratchet and thereby swinging the guard outwardly, said brace escaping from the guard and adapted to travel upwardly along the outer side thereof in the raising of the awning from its abnormal lowered position.
- 15 7. The combination with the awning fabric and its supports including a guide and an outwardly swinging arm; of a brace pivoted to said arm and extending on the upper side thereof and inwardly, a ratchet 20 with which said brace engages in the lowering of the awning, a movable guard adjacent the ratchet and behind which the brace engages, and a cam associated with the ratchet and guard for disengaging the brace from 25 the ratchet and thereby swinging the guard outwardly, said brace escaping from the guard and adapted to travel upwardly along the outer side thereof in the raising of the awning from its abnormal lowered position.
- 30 8. The combination with the awning fabric and its supports including a guide and an outwardly swinging arm; of a brace pivoted to said arm and extending on the upper side thereof and inwardly and embracing one of the awning guides with provision for limited play, a ratchet with which said brace engages in the lowering of the awning, and a movable guard adjacent the 35 ratchet and adapted to be displaced by the brace upon abnormal lowering of the awning, said brace escaping from the guard and adapted to travel upwardly along the outer side thereof in the raising of the awning from its abnormal lowered position.
- 40 9. The combination with the awning fabric and its supports including a guide and an outwardly swinging arm; of a brace pivoted to said arm and extending on the upper side thereof and inwardly, a ratchet 45 with which said brace engages in the lowering of the awning, and a guard adjacent the
- ratchet, the guard and ratchet being movably mounted and adapted to be displaced by the brace upon abnormal lowering of the awning, said brace escaping from the guard and adapted to travel upwardly along the outer side thereof in the raising of the awning from its abnormal lowered position. 55
10. The combination with the awning fabric and its supports including a guide and an outwardly swinging arm; of a brace pivoted to said arm and extending on the upper side thereof and inwardly, a ratchet 60 with which said brace engages in the lowering of the awning, and a guard adjacent the ratchet, the guard and ratchet being pivotally suspended and adapted to be displaced by the brace upon abnormal lowering of the awning, said brace escaping from the guard 65 and adapted to travel upwardly along the outer side thereof in the raising of the awning from its abnormal lowered position.
11. The combination with the awning fabric and its supports including a guide 75 and an outwardly swinging arm; of a brace pivoted to said arm and extending on the upper side thereof and inwardly, a ratchet with which said brace engages in the lowering of the awning, a guard adjacent the 80 ratchet, and a bracket to which said ratchet and guard are pivoted and which has an inclined edge adjacent the lower ends thereof, said brace adapted to be thrown outward by coaction with said bracket-edge upon abnormal lowering and to escape from behind the guard and travel upwardly along the outer side thereof in the raising of the awning from its abnormal lowered position. 85
12. The combination with the awning fabric and its supports including a guide and an outwardly swinging arm; of a brace pivoted to said arm and extending on the upper side thereof and inwardly and embracing the awning guide, said brace and arm having 90 coacting parts which limit the upward swing of the arm when the awning is raised and keep it off dead-center. 95

In testimony whereof I affix my signature in presence of two witnesses.
